VALVE SPRING LIFTER

Evan Meirion Arthur, West Heath, Birmingham,
EnglandApplication February 10, 1949, Serial No. 75,547
In Great Britain February 11, 1948

1 Claim. (Cl. 29—221)

1

This invention relates to locking means for valve spring lifters of the one-hand operated plier type, and it has for its object to provide means enabling a novel or improved construction which can be quickly and safely manipulated.

A further object of this invention is to provide means utilizing a link for operating a gripping jaw as part of the locking means.

A still further object of the invention resides in the provision of means affording the construction of the locking means as means for adjusting the opening of the jaws of the valve lifter.

Referring to the drawings:

Figure 1 is a side elevation of a valve spring lifter constructed according to this invention.

Figure 2 is a plan.

Figure 3 is a plan of the lower gripping jaw.

Figure 4 is a plan of the lower lever.

Figure 5 is a plan of the upper lever.

Figure 6 is a plan of the catch, and

Figure 7 is a side elevation of Figure 6.

According to a convenient embodiment of this invention, the valve spring lifter comprises upper and lower levers 1 and 2 which may be U-shaped in cross section at the ends forming the handles 3 and 4 and the lever 1 is straight, whilst the other lever 2 is angle shaped, and perforated lugs 5 projecting from the side walls of the upper lever 1 overlap perforated lugs 6 projecting from the side walls of the lower lever 2, and a pivot pin 1a is passed therethrough. The pivot pin lies nearer the outer ends of the levers than the inner or handle ends of the levers, to provide the necessary leverage. To the inner end of the straight or upper lever 1, a bifurcated upper gripping jaw or arm 7 is pivotally mounted at 8 intermediate its ends, and the tail of this jaw is pivotally connected to the upper end of a ratchet bar 9, the lower end of which is pivotally connected at 9a to the angle shaped lever 2 at a distance to the rear of the pivot connection of the two levers 1 and 2. A second bifurcated lower gripping jaw 10 is pivoted at 11, intermediate its ends, to the end of the lower or angle shaped lever 2 and the tail of this gripping jaw 10 is U-shaped to engage over the straight lever 1 to the rear of the pivotal connection of the levers 1 and 2. When the hand grips 3 and 4 are moved towards one another, the jaws 7 and 10 open and remain substantially parallel. If, for instance, it is considered that the jaw 7 is stationary and the hand grips 3 and 4 are moved together, the lever 2 will pivot on 9a at the bottom of the rack 9, the swinging movement of the rack permitting of this. The pivot 1a will move downwardly and the lever 2 will

also pivot on 1a and thus carry the pivot 11 downwardly. But as the tail of the jaw 10 slidably bears on the lever 1 which pivots downwardly, such tail of the jaw 10 also moves downwardly a corresponding amount to the downward movement of the pivot 11 and thus keeps the jaw 10 substantially parallel to the jaw 7. The upper gripping jaw 7 being bifurcated is formed of two arms which pass on each side of the upper or straight lever 1 which is also bifurcated. The bifurcated arms of the jaw 7 and the lever 1 are set at a distance apart and the space therebetween can be varied by adjusting the screwed pin 8 pivotally mounting the upper gripping jaw on the lever 1 which screws into a tapped hole on one arm of the lever 7. The angle shaped lever 2 is similarly bifurcated at the inner end, and the lower gripping jaw 10 is also bifurcated so that the space between two sides of the jaw can be varied by adjusting a screwed pin 11 forming pivot connection of the jaw 10 and the lever 2. In a further form the lower gripping jaw can be connected to the upper lever by means of links connected respectively to the lower jaw and the lever.

The ratchet bar 9 aforementioned passes through the bifurcation in the upper lever 1 and such upper lever has a pawl thereon in the form of a catch member which can be rotated to engage a tooth on the ratchet bar to pass between the ratchet teeth by a transverse directional movement. The rear edge of the link or ratchet bar 9 is curved so that the distance from such rear edge along the upper hand grip lever 1 to the pivot axis at 8 is the same in all positions of such lever 1 in relation to the link or rack bar 9. This catch may be in the form of a sector 12 pivotally mounted on the lever 1 and having an upturned flange 13 on the periphery, and this flange is in the form of a wedge and gradually increases in height from one side to the other, so that the levers can be locked to prevent the lifting jaws closing together in any position intermediate the distance between the teeth of the ratchet. If the levers are required to be locked in a position intermediate between two teeth, the wedge shaped rim aforementioned will give the intermediate adjustment. The catch member is returned and held in the release position by a spiral spring 14, and the catch has a projection 15 which bears against the side of the rack bar 9 to register the catch in the release position. The shape of the lifting jaws can be varied to suit any particular application and the shape of the levers may also be varied ac-

cording to the particular application. With the aforescribed valve spring lifter, the valve spring can be lifted by simply applying a gripping pressure on the hand levers, thereby ensuring a great saving of time. As the wedge catch 12 aforescribed is spring-urged into the release position, it is only necessary to grip the handles together to release the pressure on the wedge catch when it will automatically move into the release position.

Having thus described the invention, what is claimed as new and desired to be secured by Letters Patent, is:

A valve spring lifter comprising an upper hand grip lever which is substantially straight and a lower hand grip lever which is angular and each provided with a hand grip side, said lower hand grip lever being pivoted on said upper hand grip lever with the pivot located substantially intermediate the ends of the levers, an upper lifting jaw and a lower lifting jaw pivotally mounted intermediate their ends, respectively on one end of each of said upper and said lower hand grip levers, a link pivotally connected to the upper lifting jaw and to said lower hand grip lever 25 on said hand grip side of the latter and a tail piece on the lower gripping jaw slidably engaging the upper hand grip lever on the hand grip side of the latter so that said gripping jaws remain substantially parallel when moved apart, a rear edge on said link which is curved so that the distance from such rear edge along the up-

per hand grip lever to the axis of the pivotal mounting of the upper gripping jaw on the upper hand grip lever is the same in all positions of the upper hand grip lever in relation to said link, ratchet teeth on said rear edge of said link, a catch member rotatably mounted on said hand grip side of said upper hand grip lever and having a rim concentric with the axis of rotation of said catch member for slidably engaging one of said ratchet teeth, the edge of said rim being wedge shaped to engage said one ratchet tooth to hold said lifting jaws in predetermined positions of opening according to the position to which said catch member has been rotated, and spring means normally urging said catch member to rotate to a position for releasing said rim edge from said one ratchet tooth.

EVAN MEIRION ARTHUR.
